LEVI T. HOWELL, OF CAMDEN, NEW JERSEY, ASSIGNOR TO HIMSELF, WILLIAM SHARP, AND SMITH FISHER, OF SAME PLACE.

Letters Patent No. 83,967, dated November 10, 1868.

IMPROVEMENT IN RETAINING-DEVICE FOR DOORS, &c.

The Schedule referred to in these Letters Patent and making part of the same.

To all whom it may concern.:

Be it known that I, LEVI T. HOWELL, of Camden, Camden county, New Jersey, have invented an Improved Portable Retaining-Device for Shutters, Doors, &c.; and I do hereby declare the following to be a full, clear, and exact description of the same.

My invention consists of a device, constructed as fully described hereafter, so that when applied to the hinge of a shutter or door, it will retain the latter in the position to which it has been adjusted, the device being portable, cheap, and simple in its construction.

In order to enable others skilled in the art to make and use my invention, I will now proceed to describe its construction and operation, reference being had to the accompanying drawing, which forms a part of this specification, and in which—

Figure 1 represents in perspective a window-frame and shutter, with my improved retaining-device applied to the hinge of the shutter;

Figure 2, a section on the line 1-2, fig. 1;

Figures 3, 4, and 5, detached views, drawn to an enlarged scale; and

Figure 6, a perspective view of a modification.

At the inner side of a bent plate, A, near one edge of the same, is a projection, a, and on the latter is a lip or lug, b, which extends downward, parallel, or nearly parallel, with the plate A; a knob, c, being secured to the upper side of the said projection.

The device is applied to the hinge, B, of a shutter or door, as shown in the drawing, the curvature of the plate A being such, that when its ends bear upon the opposite plates of the hinge, (fig. 3,) the central portion will extend over the rib formed by the junction of

the two plates, the projection a resting upon the upper edge of the hinge, and the lug b being opposite to and bearing against the inner side of the hinge, as shown in figs. 1 and 5.

It will be apparent that so long as the plate remains in its position, bearing against both plates of the hinge, the latter, and the shutter or door to which it is attached, cannot be closed, and that no jarring to which the shutter or door is liable will be sufficient to detach the device from its place.

When the shutter is to be closed, the fastening-device is merely lifted from its place, and its loss may be prevented by securing it to one end of a chain or cord, attached at the other end to any adjacent fixture. In this case the knob may be dispensed with, as shown in fig. 6.

It will be apparent that this device may be applied to the hinges of doors, boxes, &c., and may be so formed as to retain the hinge in a partly-opened position.

I claim as my invention, and desire to secure by Letters Patent—

A retaining-device, consisting of a curved plate, A, its projection a and lug b extending from the projection parallel to the plate, all substantially as and for the purpose described.

In testimony whereof, I have signed my name to this specification, in the presence of two subscribing witnesses.

LEVI T. HOWELL.
